UNITED STATES PATENT OFFICE.

JULIUS TUTEUR, OF CLEVELAND, OHIO, ASSIGNOR, BY MESNE ASSIGNMENTS, TO THE REPUBLIC STRUCTURAL IRON WORKS COMPANY, OF CLEVELAND, OHIO, A CORPORATION OF OHIO.

SUPPORTING MEMBER FOR CONCRETE STRUCTURES.

1,206,621.

Specification of Letters Patent. Patented Nov. 28, 1916.

Application filed February 5, 1912. Serial No. 675,497.

To all whom it may concern:

Be it known that I, JULIUS TUTEUR, citizen of the United States, residing at Cleveland, in the county of Cuyahoga and State 5 of Ohio, have invented certain new and useful Improvements in Supporting Members for Concrete Structures, of which the following is a specification.

My invention relates to improvements in 10 a supporting member for concrete structures, and has for its object the provision of a hanger of simple construction, wherein the support may be varied to meet the different requirements of use, suitable adjustment is provided for the supported part, and small expense is entailed in manufacture. The present device, which is 15 commonly adapted for embedding in the lower face of a concrete beam or other structure, is of the type utilizing a keyhole opening 20 for securing adjustment for the supported part. This opening is provided in a casting of suitable shape and size, which preferably has formed upon its interior surface, or 25 floor, a rim for engaging the sides of the bolt-head and lugs for preventing the accidental displacement thereof from the keyhole opening. Over and around said casting, there is secured a light sheet metal 30 casing, having lateral openings in its inclined side-walls, registering with corresponding lateral openings in the casting, through which a bar preferably flattened 35 and of the desired length required for the supported weight, may be thrust to retain the parts in their normal relation and later support the hanger within the concrete. Attaching lugs may be provided upon the casing for securing it in position within the 40 form. Said casing, accordingly, forms a protective member for preventing the access of the concrete to the casting and bolt-head, while maintaining the hanger in position during the pouring and tamping of the concrete, and finally affording limited support 45 for said hanger within the concrete, by reason of its outwardly flaring side walls.

The device of my invention may be readily understood by considering the accompanying drawings in connection with the further specification and claims; said drawings comprising: Figure 1, illustrating the complete device in perspective; Fig. 2, showing the same in end elevation; Fig. 3, ex-

hibiting a side elevation partially in longitudinal section; Fig. 4, illustrating the casting in upper plan view, and Fig. 5, depicting the casing in an under-side plan view.

Throughout the several figures, I have 60 employed the same character of reference, to indicate similar parts.

The casting *a* is provided with a key-hole opening *b* in its floor *b'*, which is encircled by an elevated rim *a'*, and lugs *b''* mark 65 the extremities of the narrowed portion of said opening *b*. Side-pieces *c* cut by lateral openings *c'* at a sufficient height to clear the head of an inserted bolt *d*, serve to complete the said casting which comprises the principal supporting member of my improved device. The rim, *a'*, materially strengthens 70 the bottom of the casting and also prevents the bolt-head from binding or turning after it has been inserted through the key-hole 75 opening, unless said bolt is raised to clear the rim, while the lugs *b''* normally retain the bolt-head from sliding into the enlarged portion of opening *b*, after it has been inserted within the device.

The casing *e* may be of any approved type, but preferably I construct the same with lateral openings *e'* in its outwardly flaring sides, which register with the corresponding opening *c'* in the casting, and together are adapted to receive the strap or flattened bar *f* which is cut of suitable length to extend into the body of the concrete and afford the desired support, principally dependent upon the length of said 85 bar which distributes the weight through the surrounding body of concrete, at such height as said strap may be bent or laterally extended therein. The ends *e²* of said casing preferably flare outwardly, as well, and 90 are equipped with terminal ears *e³* through which nails may be driven for securing the assembled device within the form, prior to 95 pouring and tamping the concrete therein.

From a consideration of the foregoing, 100 it will be appreciated that the device herein set forth, affords for the supporting bolt, the desired adjustment within the slotted or key-hole opening, *b*, while normally retaining the bolt-head against rotation and 105 slippage from its supported position. The casting is of such size and construction as to sustain the maximum weight normally

beneath the laterally extending bar which distributes said weight throughout the body of the embedding concrete. The casing which is made from sheet or cast metal, 5 serves to prevent the access of any concrete to its interior, and thereby preserving the casting from being clogged, while adding very little to the cost of the assembled device.

10 Having now described the hanger of my invention, I claim as new and desire to secure by Letters Patent, the following:—

1. In a device of the class described, the combination with a hollow cast metal base 15 portion having upwardly extending side portions, a key-hole opening in its lower face and an elevated inner rim encircling said opening, of a headed sustaining member adapted to be inserted within the opening 20 and rim and an inclosing sheet metal casing for the body portion, substantially as set forth.

2. In a device of the class described, the combination with a cast metal body portion, 25 having a key-hole opening in its lower face, a retaining lug adjacent to the expanded portion of said opening, and an elevated continuous inner rim adjacent to the narrower portion thereof, of an associated sustaining 30 member and an inclosing sheet metal casing for said casting, substantially as set forth.

3. In a supporting member for concrete structures, the combination with a hollow cast metal base portion, having a slot in its

lower face, and upwardly extending side 35 walls with lateral openings therein, of an inclosing casing having openings in its side walls registering with those of the casting, and a transverse strap inserted through the registering openings to serve as a sustaining 40 member, substantially as set forth.

4. In a supporting member for concrete structures, the combination with a hollow cast metal base portion, having a slot in its 45 lower face, and upwardly extending side walls with lateral openings therein, of an inclosing casing having upwardly flaring walls and openings in its side walls registering with those of the casting, and a transverse strap inserted through the registering 50 openings to serve as a sustaining member, substantially as set forth.

5. A device of the class described, comprising a hollow three-sided casting, the lower face thereof being provided with a key-hole slot, surrounded by an elevated rim, and the side portions having alined 55 openings, in combination with a headed bolt adapted to be inserted within said slot, and means for covering the hollow casting, substantially as set forth.

In testimony whereof I affix my signature in presence of two witnesses.

JULIUS TUTEUR. [L.S.]
